ALAN R. FERGUSSON, OF NEW YORK, N. Y.

TANK CLOSURE

Application filed April 25, 1931. Serial No. 532,738.

This invention relates to tank closures in general, but in some respects is more particularly concerned with caps or closures of the types required for automobile gasoline tanks and radiators.

For gasoline tanks, radiators and the like, it is desirable that the cap or closure be of such a nature that it may be quickly opened and closed, that it be mounted in such a way as to prevent its becoming completely detached and lost, that it fit tightly and securely and that it be of neat and more or less ornamental appearance.

Special objects of the present invention are to attain the effects mentioned in a practical economical way, suited to present day tank constructions.

The various novel features of the invention, new combinations and arrangements of parts by which such objects are accomplished are set forth in the following specification, illustrated in the accompanying drawing and covered in the claims broadly defining the invention.

The drawing which accompanies and may be considered as forming part of the specification, illustrates a few of the many possible embodiments of the invention, it being understood that the structure may be modified as regards these particular disclosures without departure from the true spirit and broad scope of the invention.

Fig. 1 is a broken plan view of a form of the invention as constructed for application to gasoline tanks of typical or usual form; Fig. 2 is a broken sectional view as taken on substantially the plane of line 2—2 of Fig. 1, illustrating particularly the fastening of the closure in the mouth of the filling spout of the tank; Fig. 3 is a cross-sectional view as taken on the plane of line 3—3 of Fig. 2; Fig. 4 is a detached perspective view of the closure structure as about to be applied to the tank spout, the latter appearing as broken away at the base; Fig. 5 is a top plan view illustrative of a modification of the cap lifting means; Fig. 6 is a part side elevation and sectional view illustrating the application of an ornamental tank top to the cap structure.

In the structures illustrated, the closure is

made up as a unit applicable as such to existing tank spouts. This unit consists of an annular base ring or collar which can be locked down over the neck of the filling spout and a cap hingedly mounted on this base ring.

As shown more clearly in Figs. 2 and 4, the mounting ring or collar 7 is hollow at the underside to receive and fit down tightly over the inwardly curled end flange 8 of the filling spout. This flange, in present day constructions, is notched at diametrically opposite points at 9, to receive the securing lugs of a detachable tank cap and, extending from such notched portions, is provided with inclined edges 10, acting as cams, when such a cap is turned to draw it down into firmly closed position. These special features of the tank spout are utilized for fastening the mounting ring of the present tank closure in place.

Referring again particularly to Figs. 2 and 4, it will be seen that the mounting ring is provided at diametrically opposite points with downwardly extended and outwardly turned lugs or hooks 11, which will pass down through the notches 9 at the end of the filling spout and catch beneath the cam edges 10 as the ring is placed down over and then turned on the end of the spout. This cam action draws the ring solidly down into engagement over the end of the spout and the ring is then "locked" in this firmly seated relation by bending one or more locking lugs 12 at the inside of the ring outwardly from the position shown in Fig. 4 to the position indicated in Figs. 1, 2 and 3, so as to stand in the notches 9 or to interlock beneath the downturned flange in which such notches are formed. If, after the mounting ring is tightened down over the tank spout, the locking lugs register with these notches, as in the case illustrated, the lugs may then be simply bent down, so as to stand in these notches which will then prevent the ring from being turned sufficiently to enable its removal from the tank spout. On the other hand, if the locking lugs are not in register with the notches when the ring is seated on the tank spout, then they need only be bent outward to catch under

portions of the cam flange. In either event, the mounting ring is locked down over the tank spout and cannot be removed, except possibly by the use of special tools designed to operate on the locking lugs. Thus casual removal of the cap mount is prevented, but if necessary, a mechanic properly equipped with tools and knowing the structure, may effect removal of the device. As particularly shown in Fig. 4, the locking lugs may be angled as illustrated at 13, so that downward and outward force of the same will have the effect of throwing these angled portions outward as hooks to interlock with either the notched or solid portions of the cam flange. Stop shoulders, such as indicated at 14 are usually provided at the ends of the cam portions adjacent the notches and these further aid in preventing any unintended rotation and detachment of the mounting ring.

The top or cap member is designated 15 and is shown as constructed of spring sheet metal, of generally ornamental appearance and as having partially severed dependent spring fingers 16 about the rim of the same bent inwardly sufficiently to operate as claws gripping under the rounded rim portion 17 of the base ring. At one side of the rim the cap member is shown as having a dependent hood portion 18 serving as a housing over a similar projection 19 of the base ring, a pivot pin 20 extended through the dependent edges of such projecting portions serves to pivotally connect the cap with the base ring and a coiled spring 21 positioned on this pivot pin in protected relation under the hood or guard 19, serves to snap the cover open when the holding grip of the spring claws is overcome.

The spring grip of the cover may be released in various ways. By way of example, there is shown in Figs. 1 to 4 a small T-shaped lever 22, pivoted at 23, on a dependent lug portion 24 of the mounting ring, diametrically opposite the hinge, with the head 25 of this T-shaped member positioned to engage a dependent cam shaped lip 25', Fig. 4, on the cover. When rocked in either direction, the head of this T-shaped lever, 50 acting against the cam projection of the cover will force the cover open sufficiently to break the grip of the spring fingers, enabling the hinge spring to snap the cover open. As the cover is forced closed, the cam projection on the same will engage the head of the T lever, rocking the same back into the intermediate position illustrated, where it is held against rattling, in position to operate whenever required to release the cover.

If desired, the cover may be released directly by a handle lever extension, such as shown at 26 in Fig. 5, projecting from the side opposite the hinge. This lever handle may be a part of or be separately attached to the top of the cover as will be evident.

If the spring cap is not considered sufficiently ornamental, or if it is desired to provide an ornamental extra size cover, this may be accomplished by making such a cover in the desired over-size ornamental shape as indicated at 27 in Fig. 6, and attaching the same as by a rivet 28 or the like, to the closure cap. This ornamental cap may be of sufficient extent to provide of itself the leverage necessary for releasing the spring holding fingers, and may in addition, be provided with a finger grip extension 29, indicating the portion opposite the hinge to be engaged in effecting the release of the cap.

As will be plain particularly from Fig. 4, the device may be made up as a complete replacement unit to be substituted for tank caps now in use. This unit is quickly applied by simply placing it on the tank spout after the manner of the original tank cap and then turning down the locking fingers to secure it as a permanent part of the tank spout. The spring fingers hold the cap tightly and firmly closed, preventing objectionable rattle or loss of tank contents. At the same time, the cover is quickly and easily released by a simple one way lever action and may be secured by a direct closing movement. The interlocking cam action between the mounting ring and tank spout is usually sufficient to insure a tight joint between these parts, but if found desirable, a suitable gasket may be interposed between the end of the tank spout and the overstanding portion of the mounting ring. Also, a gasket may be used between the adjoining faces of the cap and mounting ring. Such a gasket is illustrated at 30, held to the underside of the cap by a washer 31 secured by a rivet 32, said washer and the central portion of the cap being illustrated as having small non-registering vents 33, 34, in the annularly ridged portions 35, 36, of the same.

While it will be clear that the invention is especially adaptable to automobile gasoline tanks, it should also be clear that the same may be adapted to and utilized for the closure of radiator spouts and in fact, as a desirable cover for many other forms of tanks and containers.

In view of the broad utility and general scope of the invention, the terms employed herein should be considered in a descriptive rather than in a limiting sense, except possibly for such limitations as may be imposed by the state of the prior art.

What is claimed is:

1. A tank closure, comprising a base ring provided with means for securing the same on the neck of a tank filling spout, and a cap pivoted at one side to said base ring and having dependent spring fingers arranged as a series extending about the periphery of the cap from said pivotal point and engageable with the base ring to peripherally yieldingly

secure said cap in cooperating closed engagement with the base ring.

2. A tank closure, comprising a base ring provided with means for securing the same on the neck of a tank filling spout, a cap pivoted at one side to said base ring and having dependent spring fingers arranged as a series extending about the periphery of the cap from said pivotal point and engageable with the base ring to peripherally yieldingly secure said cap in cooperating closed engagement with the base ring and a spring for throwing the cap open when the grip of said spring holding fingers is released.

3. A tank closure, comprising a base ring provided with means for securing the same on the neck of a tank filling spout, a cap pivoted at one side to said base ring and having dependent spring fingers arranged as a series extending about the periphery of the cap from said pivotal point and engageable with the base ring to peripherally yieldingly secure said cap in cooperating closed engagement with the base ring, means for overcoming the grip of the spring holding fingers and a spring for automatically throwing the cover to open position when the grip of the spring holding fingers is overcome.

4. A tank closure, comprising a base ring provided with means for securing the same on the neck of a tank filling spout, a cap pivoted on said base ring and having dependent spring fingers engageable with the base ring to yieldingly secure said cap in cooperating closed engagement with the base ring and cam means for forcing the cover open in opposition to the grip of the spring holding fingers.

5. A tank closure, comprising a base ring provided with means for securing the same on the neck of a tank filling spout, a cap pivoted on said base ring and having dependent spring fingers engageable with the base ring to yieldingly secure said cap in cooperating closed engagement with the base ring and a substantially T-shaped cover opening lever pivoted on the holding ring and engaging the rim of the cover at a point substantially diametrically opposite the pivotal mounting.

6. In combination, a base ring hollowed in its underside to fit over the filling spout of a tank and constructed for interlocking engagement with such a spout, a cap having spring gripping fingers for securing the same yieldingly closed over the base ring, a hinging connection between the cap and base ring and handle means for releasing the closing grip of the cap on the base ring.

7. In combination, a base ring hollowed in its underside to fit over the filling spout of a tank and constructed for interlocking engagement with such a spout, a cap having spring gripping fingers for securing the same yieldingly closed over the base ring, a hing-

ing connection between the cap and base ring, handle means for releasing the closing grip of the cap on the base ring and spring means for throwing the cover open upon the release of the closing grip aforesaid.

8. In combination with a tank spout having a notched flange, a mounting ring for cooperative engagement with the spout and having a securing element to pass the notched portion and interlock with the flange of the spout, a closure cap pivoted on said mounting ring and provided with a series of spring fingers about the periphery of the cap for yieldingly gripping the same to the mounting ring.

9. In combination with a tank spout having a notched flange, a mounting ring for cooperative engagement with the spout and having a securing element to pass the notched portion and interlock with the flange of the spout, a closure cap pivoted on said mounting ring and locking means on said mounting ring in addition to said securing element, said locking means standing in the notch of the spout flange and cooperating with the flange at one side of said notch to prevent detachment of the mounting ring from the spout.

10. A closure of the character disclosed, comprising a mounting ring applicable to the filling spout of a tank, a spring closed cap pivoted on said mounting ring, an ornamental cover attached to said cap and projecting beyond the rim of the cap to afford sufficient leverage for overcoming the spring closing force.

11. A closure of the character disclosed, comprising in combination a mounting ring of inverted U-shaped cross-section to fit over the rim of a filling spout and to provide a lip for the same, a cap hinged to said mounting ring and engageable with the lip portion of said mounting ring and a dependent spring finger on the cap yieldingly engaging down over the outer portion of the mounting ring for yieldingly retaining the cap in closed relation.

12. A closure of the character disclosed, comprising in combination, a hollow mounting ring to fit over the rim of a tank spout and to provide a lip for the same, said mounting ring having at the inside of the same, dependent means for securing said ring to the tank spout and having at the outside of the same a rounded rim portion, a cap in close fitting engagement over said hollow mounting ring, said cap having a series of dependent spring fingers about the periphery of the same, bowed to resiliently engage down over the rounded rim portion of the mounting ring and handle means associated with said cap for overcoming the holding force of the series of spring gripping fingers.

13. A closure of the character disclosed, comprising in combination, a hollow mounting ring to fit over the rim of a tank spout

and to provide a lip for the same, said mounting ring having at the inside of the same, dependent means for securing said ring to the tank spout and having at the outside of the same a rounded rim portion, a cap in close fitting engagement over said hollow mounted ring, said cap having a series of dependent spring fingers about the periphery of the same, bowed to resiliently engage down over the rounded rim portion of the mounting ring and handle means associated with said cap for overcoming the holding force of the series of spring gripping fingers, the cap having a hinge connection with the mounting ring at one side and said handle means being located substantially diametrically opposite said hinge connection.

14. A closure of the character disclosed, comprising in combination, a hollow mounting ring to fit over the rim of a tank spout and to provide a lip for the same, said mounting ring having at the inside of the same, dependent means for securing said ring to the tank spout and having at the outside of the same a rounded rim portion, a cap in close fitting engagement over said hollow mounted ring, said cap having a series of dependent spring fingers about the periphery of the same, bowed to resiliently engage down over the rounded rim portion of the mounting ring and handle means associated with said cap for overcoming the holding force of the series of spring gripping fingers, said securing means at the inside of the mounting ring including dependent hook lugs and a dependent locking lug and a tank spout having an inclined flange structure inside the same for engagement by said hook lugs, said flange structure having a locking shoulder positioned for engagement by the locking lug when the mounting ring is located on the spout with the hook lugs properly engaged with the inclined flange.

15. In combination with a tank spout having an inwardly extending and downwardly projecting flange notched through at the top and having lower inclined cam edges, a mounting ring engageable over said tank spout and having at the inside of the same dependent hook lugs to pass through notched portions of the flange and interlock beneath the inclined flange edges upon rotative movement of the mounting ring on the spout, a stop lug at the inside of the mounting ring and engageable in a notched portion of the flange at the end of such rotative movement to thereby lock the mounting ring in such position upon the tank spout, a cap hinged upon the mounting ring and readily releasable means for securely holding said hinged cap in close fitting engagement with said mounting ring.

16. In combination with a tank spout having an inwardly extending and downwardly projecting flange notched through at the top

and having lower inclined cam edges, a mounting ring engageable over said tank spout and having at the inside of the same dependent hook lugs to pass through notched portions of the flange and interlock beneath the inclined flange edges upon rotative movement of the mounting ring on the spout, a stop lug at the inside of the mounting ring and engageable in a notched portion of the flange at the end of such rotative movement to thereby lock the mounting ring in such position upon the tank spout, a cap hinged upon the mounting ring, a series of spring fingers dependent from the peripheral portion of the cap and resiliently gripping down over the outer portion of said mounting ring and means associated with said cap for overcoming the gripping force of said series of spring holding fingers.

17. In combination, a hollow mounting ring for engagement over the mouth of a tank spout, said mounting ring having a projecting hood at one side, a cap having hinge lugs aligned with the sides of said projecting hood, a pivot pin extending through said pivot lugs and the sides of the hood, spring means for yieldingly securing the cover closed against the mounting ring and a cover opening spring beneath the hood of the mounting ring and protected by said hood when the cover is thrown open by said spring.

18. In a tank closure, the combination of an annular member having at the outside a rounded rim portion, a cap hingedly connected with said member at one side and having a projecting handle at the opposite side, a series of dependent spring fingers extending from the hinge connection about the peripheral portion of the cap and bowed to yieldingly grip said peripheral portion in close fitting engagement with the mouth of the annular member and a cap opening spring associated with the hinge connection for throwing the cap open when the force of the spring gripping fingers is overcome by opening force applied to the handle aforesaid.

19. In combination with a tank spout having an internal flange notched downwardly through the top of the same and having inclined lower edge portions, a cap mounting ring seated on said spout, said ring having hook lugs to pass down through notches in the flange and engage beneath said inclined edge portions on rotation of the ring on the spout and a locking lug or lugs to pass down over the flange and bendable into one or more of said notches to lock the ring in the position to which it has been rotated, a cap and means for releasably holding said cap seated on said mounting ring.

20. In combination with a tank spout having an internal flange notched downwardly through the top of the same and having in-

clined lower edge portions, a cap mounting ring seated on said spout, said ring having hook lugs to pass down through notches in the flange and engage beneath said inclined edge portions on rotation of the ring on the spout and a locking lug or lugs to pass down over the flange and bendable into one or more of said notches to lock the ring in the position to which it has been rotated, a cap and means for releasably holding said cap seated on said mounting ring, including spring holding fingers dependent from the peripheral portion of the cap and bowed to grip down over and about the peripheral portion of the mounting ring.

21. In combination with a tank spout having an internal flange notched downwardly through the top of the same and having inclined lower edge portions, a cap mounting ring seated on said spout, said ring having hook lugs to pass down through notches in the flange and engage beneath said inclined edge portions on rotation of the ring on the spout and a locking lug or lugs to pass down over the flange and bendable into one or more of said notches to lock the ring in the position to which it has been rotated, a cap and means for releasably holding said cap seated on said mounting ring, including spring holding fingers dependent from the peripheral portion of the cap and bowed to grip down over and about the peripheral portion of the mounting ring, said cap having a hinging connection with the mounting ring, handle means for overcoming the cap closing force of the spring fingers and spring means carried by the mounting ring for throwing the cap open when so released by the handle means.

22. A closure of the character disclosed, comprising in combination, a base ring, a cap yieldingly held closed to said base ring, an annular gasket within the cap for sealing engagement with the base ring, a washer secured to the underside of the cap in position overlapping the inner edge of the annular gasket and thereby securing the gasket to the underside of the cap, said washer having a downwardly directed annularly ridged portion with a vent opening therein and the cap having an upwardly extending annularly ridged portion provided with a vent opening offset from the vent opening in the downwardly ridged portion of the washer.

23. A closure of the character disclosed, comprising in combination, a base ring, a cap yieldingly held closed to said base ring, an annular gasket within the cap for sealing engagement with the base ring, a washer secured to the underside of the cap in position overlapping the inner edge of the annular gasket and thereby securing said gasket to the underside of the cap, said washer having a downwardly ridged portion with a vent opening therein and the cap having a vent

opening therein laterally offset from the downwardly ridged vent in the gasket securing washer.

In testimony whereof I affix my signature.
